UNITED STATES PATENT OFFICE.

GEORGE O'NEILL, OF MONCTON, NEW BRUNSWICK, CANADA.

FURNACE-DOOR.

1,131,945.

Specification of Letters Patent.

Patented Mar. 16, 1915.

Application filed October 22, 1914. Serial No. 868,061.

To all whom it may concern:

Be it known that I, GEORGE O'NEILL, a subject of the King of Great Britain, and resident of Moncton, in the Province of New Brunswick, Dominion of Canada, have invented certain new and useful Improvements in Furnace-Doors, of which the following is a specification.

This invention relates to improvements in furnace doors of the type adapted to admit air to the interior of the fire-box, to promote combustion and eliminate smoke and the objects of the invention are to provide means insuring proper heating of air before it is discharged into the fire box, and further to generally simplify the construction of the door, and it consists essentially of the improved construction of door particularly described in the following specification and accompanying drawings forming part of the same.

In the drawings, Figure 1 is a sectional perspective view of the improved door mounted on a boiler. Fig. 2 is a front elevation of the improved door. Fig. 3 is a back elevation of the same. Fig. 4 is a perspective view of the inner lining member and baffle plates thereon. Fig. 5 is a perspective view of an auxiliary series of baffle plates. Fig. 6 is a longitudinal section of the improved door.

Like characters of reference refer to like parts in all the figures.

Referring to the drawings, A represents a boiler and B the improved door mounted thereon, the said boiler being of any usual type and not forming part of the present invention requires no further description.

The door B consists of the front plate C and the hollow lining member D, the former having suitable lugs 2 for hanging purposes and a central latching member 3. To provide for the passage of air through the plate C, a plurality of orifices 4 are provided extending around the outer periphery, and in the embodiment illustrated a second set of orifices 5 are shown, the object of which will be made clear hereafter.

The inner lining member D comprises a radially corrugated back plate 7 having an orifice 8 therethrough around the periphery of which a flange extends with which the conduit 9 engages, the sides of the said back plate being beveled at 10 and provided with lugs 11 having threaded orifices 12 therethrough designed to register with the ori-

fices 5 in the front plate. Located between the beveled sides 10 and the conduit 9 is a concentric baffle plate 13 integral with the corrugated back plate 7, the edges of such baffle plate remote from the said back plate being provided with a plurality of recesses 14 designed to form air passages in a manner to be hereafter described. Coöoperating with the hollow lining member D is a second set of baffles E comprising a front plate 15 having integral concentric flanges 16 and 17, the former of which is designed to frictionally engage with the lugs 11 on the said hollow lining member, such flanges being provided on the edge remote from the plate 15 with recesses 18 adapted to form air passages.

In assembling the door A the baffles E are inserted in the hollow lining member D, the flange 16 engaging with the lugs 11 and the flange 17 interposed between the flange 13 and conduit 9, thereby staggering the said baffle plates. In this position it will be seen that the edges of the flanges 13, 16 and 17 engage with the inner faces of the plate 15 and the corrugated back plate 7, the curved recesses 14 and 18 providing the necessary passages for the air. The front plate B is now placed in position with the orifices 5 registering with the orifices 12 in the lugs 11 when the said door is secured in an assembled position by means of set screws or the like.

In the operation of the door, the air enters through the orifices 4 and passing between the several baffle plates becomes thoroughly heated before being discharged through the conduit 9 into the fire box of the boiler.

The function of radially corrugating the back plate 7 of the hollow lining member is to increase the heating area of the said lining.

It will of course be understood that the number of baffle plates may be increased in the inner lining, or the auxiliary baffles E, as is found convenient or desirable.

As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A furnace door having a hollow lining member provided with a central opening, the said member being radially corrugated around the opening, concentric baffle plates in said lining, and auxiliary baffle plates frictionally retained in said lining and staggered relatively to the first.
2. A furnace door having a hollow lining member provided with a central opening, concentric baffle plates in said lining, lugs in said lining, and auxiliary concentric baffle plates frictionally supported in said lining by said lugs, and staggered relatively to the first.
3. A furnace door having a hollow lining member provided with a central opening, concentric baffle plates in said lining having recesses in the edges, lugs on said lining member, auxiliary baffle plates frictionally retained in said lining and having recesses in the edges, such baffle plates being staggered relatively to the first.
4. A furnace door having a hollow lining member provided with a central opening, 25 said member being radially corrugated around the said opening, a flange around the inner periphery of the said opening, a conduit engaging with said flange forming a discharge end, and concentric baffle plates 30 in the said door.
5. A furnace door having a front plate provided with a plurality of air inlet ori-fices around the outer periphery, a hollow lining member provided with a central 35 opening, said member being radially cor-rugated around the said opening, a concen-tric baffle plate on said lining, auxiliary baffle plates frictionally supported in said lining and staggered relatively to the first 40 said baffle.

In witness whereof I have hereunto set my hand in the presence of two witnesses.

GEORGE O'NEILL.
